US00D648217S

(12) **United States Design Patent**
Fahey et al.

(10) **Patent No.:** **US D648,217 S**
(45) **Date of Patent:** **** Nov. 8, 2011**

(54) **BALL-SHAPED BOTTLE WITH SECONDARY CAVITY**

(75) Inventors: **Lonnie Joseph Fahey**, Belle Plaine, MN (US); **William Paul Weber**, Chanhassen, MN (US); **Martin T. Geithmann**, Maumee, OH (US)

(73) Assignee: **Emergent Technologies, L.L.C.**, Chanhassen, MN (US)

(**) Term: **14 Years**

(21) Appl. No.: **29/379,453**

(22) Filed: **Nov. 19, 2010**

(51) **LOC (9) Cl. 09-01**

(52) **U.S. Cl. D9/500; D9/519; D9/520; D9/745**

(57) **CLAIM**

The ornamental design for a ball-shaped bottle with a secondary cavity, as shown and described.

DESCRIPTION

FIG. 1 is a perspective view of a ball-shaped bottle with a secondary cavity.

FIG. 2 is a side view of the ball-shaped bottle with a secondary cavity.

FIG. 3 is a top view of the ball-shaped bottle with a secondary cavity.

FIG. 4 is a bottom view of the ball-shaped bottle with a secondary cavity; and,

FIG. 5 is a cross-section view of the lower portion of the ball-shaped bottle with secondary cavity.
